(57) **ABSTRACT**

A construction toy system including a plurality of modular assembly pieces and a plurality of pivotal-rods. Each of the pivotal-rods includes an identical engaging rod-tips on each end thereof. Each of the assembly pieces have identical thickness and a circumferential edge. A number of straight receiving grooves are formed, inwardly, at the circumferential edge, wherein the identical thickness is predesigned to fittingly fill the gap formed by the straight receiving groove. A select assembly piece is configured to interlock with another assembly piece via the straight receiving grooves of both selected assembly pieces. A selected assembly pieces may have at least one identical circular through hole formed at a central location with respect to the lateral dimension of the assembly pieces, wherein an engaging rod-tip of a selected pivotal-rod may engage with a selected circular through hole of the selected assembly piece.

MODULAR TOY CONSTRUCTION SYSTEM

CROSS REFERENCE TO RELATED APPLICATIONS

This application is a U.S. National Stage Entry under 35 U.S.C. § 371 of International Application No. PCT/IL2021/051001 filed Aug. 17, 2021 entitled "MODULAR TOY CONSTRUCTION SYSTEM," which claims priority to and the benefit of U.S. Provisional Patent Application Ser. No. 63/072,254 filed on Aug. 31, 2020. The contents of each application are incorporated herein by reference in their entireties.

FIELD OF THE INVENTION

The present invention relates to parts for constructing real or imaginary objects and more particularly, to parts (pieces) which can be assembled together and combined with each other so as to construct existing or imaginary structure forms.

BACKGROUND OF THE INVENTION AND PRIOR ART

There are many different types of building sets currently on the market including, but not limited to LEGO®, Tinker Toys® and K'NEXO. LEGO® uses interlocking bricks that can be used to form a vast range of real or imaginary objects in a manner which more or less corresponds to a desired form. Both the Tinker Toys® and K'NEXO systems tend to be hub based, which have hubs that are interconnected with struts to form structures.

What is needed is a new and unique building set that gives children additional ways in which to be creative, including the ability to use objects and materials that children already have for incorporation within the creations they make. It would be further advantageous to be able to form a vast number of real or imaginary structures, wherein at least some portions of the structure can be moved and continuously change the structure form. The present invention solves these needs, among other abilities.

Additional objects, advantages and novel features of the invention will be set forth in part in the description which follows and in part will become apparent to those skilled in the art upon examination of the following or may be learned by practice of the invention. The objects and advantages of the invention may be realized and attained by means of the instrumentalities and combinations particularly pointed out in the appended claims.

SUMMARY OF THE INVENTION

The present disclosure provides an improved set of construction toy assembly pieces having a number of different structural interlocking pieces that are configured for snapping together to thereby form two-dimensional or three-dimensional structures. The construction toy pieces have one or more connecting grooves, slots and or holes formed in predesigned location that are configured for interlocking with other construction pieces. The pieces are made of strong and resilient materials.

The toy construction set of the present disclosure includes a plurality of game assembly pieces in various shapes and preconfigured thickness. Embodiments, however, are not limited to the disclosed set of game assembly pieces, and may encompass other shapes that fall within the spirit and

2

scope of the principles of this disclosure. Each game assembly piece may be provided with a color and may be composed of any suitable material that will fall within the spirit and scope of the principles of this disclosure.

5 According to teachings of the present disclosure there is provided a construction toy system including a plurality of modular assembly pieces and a plurality of pivotal-rods. Each of the pivotal-rods includes an elongated cylindrically shaped central member and including identical engaging rod-tips on each end thereof. Each of the assembly pieces have identical thickness and a circumferential edge.

10 A number of straight receiving grooves are formed, inwardly, at the circumferential edge, and wherein the identical thickness is predesigned to fittingly fill the gap formed by the straight receiving groove, wherein a select assembly piece of the plurality of assembly pieces is configured to interlock with another assembly piece via respectively selected straight receiving grooves of both selected assembly pieces.

15 The circumferential edge may be straight, round or a combination thereof.

A round edge may be a circular edge.

20 Preferably, an elongated edge includes two elongated parallel edge segments.

25 Preferably, the assembly pieces have at least one identical circular through hole that is formed at a central location with respect to the lateral dimension of the assembly pieces, wherein a selected pivotal-rod of the pivotal-rods is configured to interlock with a selected assembly piece by engaging a selected engaging rod-tip of the select pivotal-rod with a selected circular through hole of the selected assembly piece.

30 Optionally, the at least one of the assembly pieces has at least one identical cylindrical peg that is protruding form that at least one assembly piece, and wherein the cylindrical peg is configured to interlock with a selected circular through hole of another selected assembly piece.

35 Optionally, at least one of the assembly pieces has at least one identical cylindrical peg that is protruding form the at least one assembly piece, and wherein the cylindrical peg is configured to interlock with a selected pivotal-rod by engaging the peg of the pivotal-rod with a cavity of the selected pivotal-rod.

40 Preferably, the plurality of modular assembly pieces are predesigned to have a proportional symmetry therebetween the assembly pieces, wherein the lengths of the respective assembly pieces is either the same or multiplied by an integer.

45 Preferably, the plurality of modular assembly pieces are predesigned to have a proportional symmetry therebetween the assembly pieces, wherein the lengths of the respective assembly pieces is either the same or multiplied by an integer.

50 Preferably, the plurality of modular assembly pieces are predesigned to have a proportional symmetry therebetween the assembly pieces, wherein the lengths of the respective assembly pieces is either the same or multiplied by an integer. It should be appreciated that the proportional symmetry therebetween the distance between adjacent the circular through holes, provides the construction toy system with the required modularity.

55 Preferably, the plurality of modular assembly pieces are predesigned to have a proportional symmetry therebetween the distance between adjacent the circular through holes formed in the respective assembly pieces is either the same or multiplied by an integer.

Optionally, selected pivotal-rod of the pivotal-rods is configured to interlock with another pivotal-rod by engaging a selected engaging rod-tip of the selected pivotal-rod engaging with a cavity of the other pivotal-rod.

Optionally, the plurality of modular assembly pieces are selected from a group of assembly pieces including a flat-stick piece, a connector-pieces, a flat wheel piece, a flat U-shaped piece, a narrow upright U-shaped piece, a wide upright U-shaped piece, a flat L-shaped piece, a flat traversed-Z-shaped piece, an upright T-shaped piece, a flat bow-shaped piece, an upright bow-shaped piece, a flat ring-shaped piece, a flat oval-shaped piece, an upright ring-shaped piece and an upright oval-shaped piece.

BRIEF DESCRIPTION OF THE DRAWINGS

FIG. 1a is a perspective view of an example embodiment of a first basic flat-stick piece, according to variations of the present disclosure.

FIG. 1b is a perspective view of an example embodiment of a second basic flat-stick piece, according to variations of the present disclosure.

FIG. 1c is a perspective view of an example embodiment of a third basic flat-stick piece, according to variations of the present disclosure.

FIG. 1d is a perspective view of an example embodiment of a fourth basic flat-stick piece, according to variations of the present disclosure.

FIG. 1e is a perspective view of an example embodiment of a fifth basic flat-stick piece, according to variations of the present disclosure.

FIG. 1f is a perspective view of an example embodiment of a sixth basic flat-stick piece, according to variations of the present disclosure.

FIG. 1g is a perspective view of an example embodiment of a seventh basic flat-stick piece, according to variations of the present disclosure.

FIG. 2a is a perspective view of an example embodiment of a first narrow flat-stick piece, according to variations of the present disclosure.

FIG. 2b is a perspective view of an example embodiment of a second narrow flat-stick piece, according to variations of the present disclosure.

FIG. 2c is a perspective view of an example embodiment of a third narrow flat-stick piece, according to variations of the present disclosure.

FIG. 2d is a perspective view of an example embodiment of a fourth narrow flat-stick piece, according to variations of the present disclosure.

FIG. 2e is a perspective view of an example embodiment of a fifth narrow flat-stick piece, according to variations of the present disclosure.

FIGS. 3a-3d are perspective view illustrations of perspective view of example embodiments of connector-pieces, according to variations of the present disclosure.

FIG. 4a is a perspective view illustration of an example flat wheel piece, having a hole formed at the center and configured to receive a matching pivotal-rod, according to variations of the present disclosure.

FIG. 4b is a perspective view illustration of an example wheel piece, having a flat face on a first side and a terraced face on the second side, and having a hole formed at the center and configured to receive a matching pivotal-rod, according to variations of the present disclosure.

FIG. 4c is a perspective view illustration of an example flat wheel piece, having a connecting peg protruding from

center of one face perpendicular thereto, according to variations of the present disclosure.

FIG. 4d is a perspective view illustration of an example flat wheel piece, having a connecting pin protruding from center of one face perpendicular thereto, according to variations of the present disclosure, wherein the end of the connecting pin is split into two or more sections.

FIG. 4e is a perspective view illustration of an example flat disc piece, according to variations of the present disclosure.

FIG. 5a is a perspective view of an example embodiment of a pivotal-rod piece, according to variations of the present disclosure.

FIG. 5b is a perspective view of an example pivotal-rod piece as having two cylindrical cavities formed at two ends of the elongated cylindrical body. FIG. 5b further illustrates that an engaging rod-tip of an example pivotal-rod piece as in FIG. 5a, may be inserted into a respective cavity.

FIG. 5c is a perspective view of an example pivotal-rod piece as in FIG. 5b, wherein a cylindrical peg of flat wheel piece as shown in the example flat wheel piece shown in FIG. 4c, may be inserted into a respective cavity of pivotal-rod piece.

FIG. 5d is a perspective view of an example pivotal-rod piece as in FIG. 5a, wherein pairs of lateral grooves are formed in the cylindrical body of the pivotal-rod piece.

FIG. 5e is a perspective view of an example pivotal-rod piece as in FIG. 5a, wherein one connecting peg is a split connecting peg.

FIG. 6 is a perspective view illustration of an example flat U-shaped piece, according to variations of the present disclosure.

FIG. 7a is a perspective view illustration of an example narrow upright U-shaped piece, according to variations of the present disclosure.

FIG. 7b is a perspective view illustration of an example wide upright U-shaped piece, according to variations of the present disclosure, having an elongated middle section and short arms.

FIG. 8 is a perspective view illustration of an example flat L-shaped piece, according to variations of the present disclosure.

FIG. 9 is a perspective view illustration of an example flat traversed-Z-shaped piece, according to variations of the present disclosure.

FIG. 10 is a perspective view illustration of an example upright T-shaped piece, according to variations of the present disclosure.

FIG. 11a is a perspective view illustration of an example flat bow-shaped piece, according to variations of the present disclosure.

FIG. 11b is a perspective view illustration of an example upright bow-shaped piece, according to variations of the present disclosure.

FIG. 11c is a perspective view illustration of an example upright bow-shaped piece, according to variations of the present disclosure, having at least one connecting pin.

FIG. 11d is a perspective view illustration of an example flat ring-shaped piece, according to variations of the present disclosure.

FIG. 11e is a perspective view illustration of an example flat oval-shaped piece, according to variations of the present disclosure.

FIGS. 12a and 12b illustrate preferred proportional symmetry among members of non-limiting example groups of selected assembly pieces.

FIG. 13a is a perspective view illustration of an example of three pairs of second and third basic flat-sticks, interconnected at the ends to facilitate scissors motion, according to variations of the present disclosure, wherein the scissors structure is shown in an elongated stretched position.

FIG. 13b is a perspective view illustration of an example of three pairs of second and third basic flat-sticks, interconnected at the ends to facilitate scissors motion, according to variations of the present disclosure, wherein the scissors structure is shown in a broad contracted position.

FIG. 14a is a perspective view illustration showing an example embodiment of a construction in a form of an aircraft, according to variations of the present disclosure, wherein the elongate body is using second basic flat-sticks that are slightly bent.

FIG. 14b is a perspective view illustration showing another example embodiment of a construction in a form of a tri-wheels scooter, wherein the elongate body is using a pair of second and third basic flat-sticks that are slightly bent.

FIG. 14c is a perspective view illustration showing another example embodiment of a construction in a form of another tri-wheels scooter.

FIG. 15 is a perspective view illustration showing another example embodiment of a construction, using a number of example upright bow-shaped pieces as shown in FIGS. 10b and 10c.

FIG. 16 is a perspective view illustration showing another example embodiment of a construction, using a number of example upright bow-shaped pieces as shown in FIG. 10a.

FIG. 17 is a perspective view illustration showing another example embodiment of another example construction.

FIG. 18 is a perspective view illustration showing another example embodiment of a construction, simulation a 4-wheels cannon.

FIG. 19 is a perspective view illustration showing another example embodiment of a construction, simulation a 4-wheels wagon, wherein each pair of wheels (front and rear) can rotate 360 degrees.

FIGS. 20a-20d illustrate a 4-wheels wagon similar to the 4-wheels wagon shown in FIG. 18 with additional pointing parts, showing the wagon in four different positions.

FIGS. 21a-20c illustrate another example embodiment of another example structure having moving parts, in three different positions.

DETAILED DESCRIPTION OF THE PREFERRED EMBODIMENTS

The present invention will now be described more fully hereinafter with reference to the accompanying drawings, in which preferred embodiments of the invention are shown. It should be appreciated however, that the disclosed set of modular game assembly pieces is not limited to the set shown herein, and may encompass other shapes that fall within the spirit and scope of the principles of this disclosure. Each game assembly piece may be provided with a color and may be composed of any suitable material that will fall within the spirit and scope of the principles of this disclosure.

The toy construction set of the present disclosure includes a plurality of modular game assembly pieces in various shapes and a preconfigured identical thickness. Embodiments, however, are not limited to the disclosed set of game assembly pieces, and may encompass other shapes that fall within the spirit and scope of the principles of this disclosure. Each game assembly piece may be provided with a

color and may be composed of any suitable material that will fall within the spirit and scope of the principles of this disclosure.

Each game assembly piece of the toy construction set 5 includes at least one element that facilitates that assembly piece to interact/interlock with at least one other game assembly piece. Furthermore, each game assembly piece has a preconfigured identical thickness (t, see FIG. 1a). It should be appreciated the thickness of an assembly piece may vary 10 at location that do not interact with any other assembly piece.

Reference is now made to the drawings. FIGS. 1a-1f show a perspective view of sample example embodiments of a basic flat-stick piece type 100, according to variations of the 15 present disclosure. Each basic flat-stick piece 100 includes a pair of elongated flat faces, preferably parallel, having a longitudinal axis 105. A basic flat-stick piece type 100 includes two straight elongated parallel edges 101a and a two round edges 101b at each end of basic flat-stick piece 20 type 100, wherein the straight elongated parallel edges 101a and the two round edges 101b form a circumferential edge 101. A number of straight receiving grooves 102 are formed, inwardly, at the straight elongated parallel edges 101a. The receiving grooves 102 are typically, with no limitation, equally spaced apart. The width of each receiving groove 102 is preconfigured to receive other game assembly pieces, wherein the width of each receiving groove 102 is preconfigured to fittingly receive the thickness dimension (t) of the received game assembly piece. The number of straight 30 receiving grooves 102 formed on each side may vary.

Typically, a circular through hole is formed at the center of the round end edges 101b of the basic flat-stick piece type 100, wherein a straight end groove is formed at a preconfigured location of the round edge and extends through the 35 hole formed at the center of the respective round edge.

FIG. 1a is a perspective view of an example embodiment of a first basic flat-stick piece 100a, wherein the straight end groove 104 is formed along the longitudinal axis 105 and ends with a circular through hole 103. FIG. 1b is a perspective view of an example embodiment of a second basic flat-stick piece 100b, that is similar to a first basic flat-stick piece 100a, but has additional one or more circular through holes 110 that are formed along the longitudinal axis 105. FIG. 1c is a perspective view of an example embodiment of a third basic flat-stick piece 100c, that is similar to first basic flat-stick piece 100a, but has additional one or more cylindrical pegs 112 that are protruding perpendicular to one of the two faces of third basic flat-stick piece 100c, along the longitudinal axis 105. Each cylindrical peg 112 is configured to be fittingly inserted into circular through holes 110. FIG. 1d is a perspective view of an example embodiment of a fourth basic flat-stick piece 100d, that is similar to third basic flat-stick piece 100c including cylindrical pegs 112, but has additional one or more cylindrical pegs 113 that are 50 protruding perpendicularly away from one both straight elongated parallel edges 101a of fourth basic flat-stick piece 100d, perpendicular to the longitudinal axis 105. Each cylindrical peg 113 is configured to be fittingly inserted into circular through holes 110.

FIG. 1e is a perspective view of an example embodiment of a fifth basic flat-stick piece 100e, that is similar to second basic flat-stick piece 100b, but the straight end groove 106 is formed at an angle off the longitudinal axis 105 and ends with a circular through hole 103. FIG. 1f is a perspective view of an example embodiment of a sixth basic flat-stick piece 100f, but the straight end groove 107 is formed 55 perpendicular to the longitudinal axis 105 and ends with a

circular through hole **103**. FIG. 1g is a perspective view of an example embodiment of a seventh basic flat-stick piece **100g**, that is similar to first basic flat-stick piece **100b**, but instead of additional one or more circular through holes **110** laying T-shaped through openings **108** are formed along the longitudinal axis **105**.

FIGS. 2a-1e show a perspective view of sample example embodiments of a narrow flat-stick piece type **150**, according to variations of the present disclosure. Typically, with no limitations, the length of a narrow flat-stick piece type **150** is half the length of a basic flat-stick piece type **100**.

Each narrow flat-stick piece **150** includes a pair of elongated flat faces having a longitudinal axis **155**. A narrow flat-stick piece **150** includes two straight elongated parallel edges **151a** and two round edges **151b** at each end of narrow flat-stick piece type **150**, wherein the straight elongated parallel edges **151a** and the two round edges **151b** form a circumferential edge **151**. A number of straight receiving grooves **102** may be formed, inwardly, at the straight elongated parallel edges **151a**. The receiving grooves **102** are typically, with no limitation, equally spaced apart.

Typically, a circular through hole **110** is formed at the center of the round edges **151b** of the narrow flat-stick piece type **150**, wherein a straight end groove may be formed at a preconfigured location of the round edge **151b** and through the hole formed at the center of the respective round edge **151b**.

FIG. 2a is a perspective view of an example embodiment of a first narrow flat-stick piece **150a**, wherein a number of straight receiving grooves **102** are formed, inwardly, at the straight elongated parallel edges **151a**. FIG. 2b is a perspective view of an example embodiment of a second narrow flat-stick piece **150b**, that is similar to first narrow flat-stick piece **150a**, wherein the straight end groove **154** is formed at a preconfigured location of the round edge and extends along the longitudinal axis **155** and through a circular hole formed at the center of the respective round edge. FIG. 2c is a perspective view of an example embodiment of a third narrow flat-stick piece **150b**, that has no straight receiving grooves **102**, but has slots formed along the longitudinal axis **155**. FIG. 2d is a perspective view of an example embodiment of a fourth narrow flat-stick piece **150c**, that is similar to first narrow flat-stick piece **150a**, but also has straight receiving grooves **102**. FIG. 2e is a perspective view of an example embodiment of a fifth narrow flat-stick piece **150d**, but the straight receiving grooves **102** are replaced by wide receiving grooves.

FIGS. 3a-3d are perspective view illustrations of non-limiting examples of connector-pieces **180** configured to interconnect two or more game assembly pieces. FIG. 3a illustrates of perspective view of example embodiments of connector-piece **180a** that includes two straight receiving grooves **102** and thus, can connect only two game assembly pieces. FIG. 3b illustrates of perspective view of example embodiments of connector-piece **180b** that includes four straight receiving grooves **102**, one on each side of connector-piece **180b**, wherein all four corners are rounded. FIG. 3c illustrates of perspective view of example embodiments of connector-piece **180c** that includes four straight receiving grooves **102** and thus, can connect up to four game assembly pieces. FIG. 3d illustrates of perspective view of example embodiments of connector-piece **180d** that includes eight straight receiving grooves **102** and a hole **110** and thus, can connect more game assembly pieces.

FIGS. 4a-4e are perspective view illustrations of non-limiting examples of a variety of wheels **200** configured to allow relative rotational motion. Preferably, the thickness of

wheels **200** is also t. typically, all wheels **200** have a number of straight receiving grooves **102** are formed, inwardly, at the circular edge **201** of respective wheels.

FIG. 4a is a perspective view illustration of an example 5 flat wheel piece **200a**, having a hole **210** formed at the center of the wheel and configured to receive a matching peg **112** or pivotal-rod, according to variations of the present disclosure. Typically, flat wheel piece **200a** includes a pair of circular flat faces **202**, preferably parallel to each other, and 10 having a longitudinal axis **505**. A flat wheel piece **200a** includes circular circumferential edge **201** wherein a number of straight receiving grooves **102** are formed, inwardly, at the circular circumferential edge **201**. A circular through hole **110** is formed at the center of flat wheel piece **200a** at 15 the longitudinal axis **205**.

FIG. 4b is a perspective view illustration of an example 20 wheel piece **200b** is similar to flat wheel piece **200a** except that it has a thicker center section forming a terraced face **204** on one side of wheel piece **200b**, for strength.

FIG. 4c is a perspective view illustration of an example 25 flat wheel piece **200c** is similar to flat wheel piece **200a**, but instead of a cylindrical hole **210** it has a cylindrical peg **212** protruding at the center of the wheel, outwardly, perpendicular to one of the two faces **202** of flat wheel piece **200c**, along the longitudinal axis **205**.

FIG. 4d is a perspective view illustration of an example 30 flat wheel piece **200d**, having a connecting split peg **214** that is split at least into two parts (4 parts in the non-limiting example shown in FIG. 4d) and protruding outwardly from the center of one of the two faces **202**, perpendicular thereto, according to variations of the present disclosure, wherein the end of the connecting pin is split into two or more sections. It should be appreciated that pegs **212** and **214** can be inserted through any of the holes **110** or **210**, whereas split 35 peg **214** interlocks when inserted through a hole **110** or **210**.

FIG. 4e is a perspective view illustration of an example 40 flat circular disc piece **182**, according to variations of the present disclosure, that can be used as a connecting piece.

FIGS. 5a-5c are perspective view illustrations of non-45 limiting examples of pivotal-rod pieces **250** that may also fittingly interconnect two game assembly pieces that have corresponding circular holes formed therein. Typically, pivotal-rod pieces **250** have an elongated cylindrical body **260**, and may be provided with a variety of lengths. The engaging 50 rod-tips **262** of the pivotal-rod pieces **250** are cylindrical and configured to be inserted into a hole such as holes **110** and **210**, wherein the respective engaging rod-tip **262** is either fittingly inserted into a respective hole **110**, or rotatably inserted into a respective hole **110** or **210**, such that rotational motion can be formed between the pivotal-rod piece **250** and the game assembly piece in which the corresponding 55 respective hole **110** or **210** is formed.

FIG. 5a is an example of pivotal-rod piece **250a** has two 60 engaging rod-tips **262**, extending away from the elongated cylindrical body **260**, and that are used similarly to the usage of pegs **112**. FIG. 5b is an example of pivotal-rod piece **250b** having two cylindrical cavities **252** formed at two ends of the elongated cylindrical body **260** wherein cylindrical cavities **252** are configured to receive either a fitted peg such as 65 cylindrical pegs **112** or **212**, or an engaging rod-tip **262**. Example pivotal-rod piece **250b** may further have pairs of lateral grooves **254** formed in the cylindrical body **260**, wherein each pair of lateral grooves **254** is configured receive another game assembly piece. It should be appreciated that such pairs of lateral grooves **254** may be formed in any type 70 of pivotal-rod piece **250** having an elongated cylindrical body **260**, as shown in FIGS. 5d and 5e with regards to

pivotal-rod piece **250d** and **250e**, respectively. FIG. **5b** further illustrates that an engaging rod-tip **262** of pivotal-rod piece **250a** may be inserted into a cavity **252** pivotal-rod piece **250b**. similarly, FIG. **5c** further illustrate that a cylindrical peg **212** of flat wheel piece **200c** may be inserted into a cavity **252** of pivotal-rod piece **250b**.

FIG. **5e** further illustrates that an engaging rod-tip **264**, which illustrate a split connecting peg **264** that is split into at least two parts (4 parts in the non-limiting example shown in FIG. **5e**), and facilitates an interlock connection with other game assembly pieces, for example, with a flat wheel piece **200a**.

FIG. **6** is a perspective view illustration of an example flat U-shaped piece **310**, according to variations of the present disclosure.

FIG. **7a** is a perspective view illustration of an example narrow upright U-shaped piece **300**, according to variations of the present disclosure.

FIG. **7b** is a perspective view illustration of an example wide upright U-shaped piece **302**, according to variations of the present disclosure, having an elongated middle section **306** and short arms **304**.

FIG. **8** is a perspective view illustration of an example flat L-shaped piece **320**, according to variations of the present disclosure.

FIG. **9** is a perspective view illustration of an example flat traversed-Z-shaped piece **330**, according to variations of the present disclosure.

FIG. **10** is a perspective view illustration of an example upright T-shaped piece **340**, according to variations of the present disclosure.

FIG. **11a** is a perspective view illustration of an example flat bow-shaped piece **350**, according to variations of the present disclosure.

FIG. **11b** is a perspective view illustration of an example upright bow-shaped piece **360**, according to variations of the present disclosure.

FIG. **11c** is a perspective view illustration of an example upright bow-shaped piece **362**, according to variations of the present disclosure, having at least one connecting pin.

FIG. **11d** is a perspective view illustration of an example flat ring-shaped piece **370**, according to variations of the present disclosure. It should be appreciated that a ring-shaped piece may also have an upright form, similar to upright bow-shaped piece **360**, shown in FIG. **11b**.

FIG. **11e** is a perspective view illustration of an example flat oval-shaped piece **372**, according to variations of the present disclosure. It should be appreciated that an oval-shaped piece may also have an upright form, similar to upright bow-shaped piece **360**, shown in FIG. **11b**.

FIGS. **12a** and **12b** illustrate preferred proportional symmetry among members of non-limiting example groups of selected assembly pieces.

It should be appreciated that the proportional symmetry provides the construction toy system with the required modularity. As exemplified in the figures, the modular assembly pieces shown are predesigned to have a proportional symmetry therebetween the assembly pieces, wherein the lengths of the respective assembly pieces are either the same or multiplied by an integer. More so, the modular assembly pieces are predesigned to have a proportional symmetry therebetween the distances between respective adjacent circular through hole (**103**, **110**) formed in the respective assembly pieces is either the same or multiplied by an integer. It should be further appreciated that the modularity of construction toy system also facilitated the

assembly of complex structures utilizing the modular assembly pieces of the present disclosure.

In both example figures (FIG. **12a**) the selected pieces are compared in length with a basic flat-stick piece type **100**, in this example basic flat-stick piece type **100b** type **100c**. In this non limiting example, the distance factor between adjacent said circular through holes is 1:2, that is, for example two flat U-shaped pieces can be placed, side-by-side, on top of a single basic flat-stick piece **100**. In other example groups of assembly pieces (FIG. **12b**), while a single flat bow-shaped piece **350** can be placed on top of a single basic flat-stick piece **100**, two half-form flat bow-shaped pieces **350'** (see FIG. **12b**) can be placed on top of a single basic flat-stick piece **100**. It should be appreciated that other integer distance factors may be used.

FIG. **13a** is a perspective view illustration of an example of three pairs of second (**100b**) and third (**100c**) basic flat-sticks, interconnected at the ends to facilitate scissors motion, according to variations of the present disclosure, wherein a scissors structure **480** is shown in an elongated stretched position. FIG. **13b** illustrates the example of three pairs of second (**100b**) and third (**100c**) basic flat-sticks, wherein the scissors' structure **480** is shown in a broad contracted position. It should be appreciated that the scissors' structure and motion is facilitated by the modularity of the construction toy system.

FIG. **14a** is a perspective view illustration showing an example embodiment of a construction **400** in a form of an aircraft, according to variations of the present disclosure, wherein the elongate body is using second basic flat-sticks **100b** that are slightly bent, to demonstrate the resiliency of the materials from which the game assembly pieces are preferably made of.

FIG. **14b** is a perspective view illustration showing another example embodiment of a construction **410** in a form of a tri-wheels scooter, wherein the elongate body is using a pair of second (**100b**) and third (**100c**) basic flat-sticks that are slightly bent. FIG. **14c** is a perspective view illustration showing another example embodiment of a construction **412** in a form of another tri-wheels scooter.

FIG. **15** is a perspective view illustration showing another example embodiment of a construction **420**, using a number of example upright bow-shaped pieces **360** and **362**.

FIG. **16** is a perspective view illustration showing another example embodiment of a helical construction **430**, using a number of example upright bow-shaped pieces **350**.

FIG. **17** is a perspective view illustration showing another example embodiment of another example construction **440**. It should be appreciated the set of game assembly pieces of the present disclosure allows myriads of construction possibilities.

FIG. **18** is a perspective view illustration showing another example embodiment of a construction **440**, simulation a 4-wheels cannon.

FIG. **19** is a perspective view illustration showing another example embodiment of a construction **450**, simulation a 4-wheels wagon. The 4-wheels wagon **450** includes: a front pair of wheels **200a** interconnected by a pivotal-rod piece **250a**, wherein a narrow upright U-shaped piece **300₁** is mounted onto the pivotal-rod piece **250a**; a rear pair of wheels **200a** interconnected by another pivotal-rod piece **250a**, wherein a narrow upright U-shaped piece **300₂** is mounted onto the other pivotal-rod piece **250a**; and a third (**100c**) basic flat-stick that pivotally interconnects the two pair of narrow upright U-shaped piece (front **300₁** and rear

11

300₂) wherein each pair of narrow upright U-shaped piece (front **300₁** and rear **300₂**) can rotate 360 degrees about each other.

FIGS. 20a-20d illustrate a 4-wheels wagon **500** similar to the 4-wheels wagon **450** but with additional parts: showing the wagon in four different positions: an initial tandem position (FIG. 20a), a first intermediate side-by-side position (FIG. 20b), a second intermediate tandem position (FIG. 20c), and an end side-by-side position (FIG. 20d). The third (100c) basic flat-stick is replaced by a second-basic flat-stick **100b₁**, and another second-basic flat-stick **100b**, being a pointer flat-stick **100b₂**. The rotational abilities of 4-wheels wagon **500** are respectively provided by three pivotal connecting flat wheel pieces **200c**: wheel piece **200c₁** provides rotational abilities to narrow upright U-shaped piece **300₁**, wheel piece **200c₂** provides rotational abilities to narrow upright U-shaped piece **300₂**, and wheel piece **200c₃** simply attaches pointer flat-stick **100b₂** to basic flat-stick **100b₁**. Pointer flat-stick **100b₂** indicates the rotation state. It should be appreciated that the motion of 4-wheels wagon **500** is facilitated by the modularity of the construction toy system.

As the front upright U-shaped piece **300₁** is moved counterclockwise, second-basic flat-stick **100b₁** rotates about narrow upright U-shaped piece **300₂** (that in this non-limiting example stands still) utilizing wheel piece **200c₂**. As second-basic flat-stick **100b₁** completes 90° of rotation, the 4-wheels wagon **500** reaches the first intermediate side-by-side position of the two sets of wheels, as shown in FIG. 20b. Similarly, as second-basic flat-stick **100b₁** continuous to rotate about narrow upright U-shaped piece **300₂**, the 4-wheels wagon **500** reaches the second intermediate tandem position of the two sets of wheels, as shown in FIG. 20c, and then to the end side-by-side position, as shown in FIG. 20d.

FIGS. 21a-21c illustrate another example embodiment of another example structure **600** having moving parts, in three different positions: an initial position (FIG. 21a), an intermediate position (FIG. 21b), and an end position (FIG. 21c). Structure **600** includes a flat wheel piece **200c** that has a cylindrical peg **212** protruding at the center of the wheel (the peg is hidden in this view), a first basic flat-stick piece **100a**, two third basic flat-stick pieces **100c** and a flat bow-shaped piece **350**. The flat bow-shaped piece **350** is connected at one end to via a first circular through hole **103** to an end cylindrical peg **112** of one flat-stick piece **100c₁** and the second end of flat bow-shaped piece **350** is connected via the second circular through hole **103** of the flat bow-shaped piece **350** to a cylindrical peg **112** of the second flat-stick piece **100c₂**. The first flat-stick piece **100c₁** is connected (not visible in the figures) via an end hole through hole **103** to the cylindrical peg **212** of flat wheel piece **200c**; and the second flat-stick piece **100c₂**. The first flat-stick piece **100c₁** is connected via an end cylindrical peg **112** being rotatably inserted to a circular through hole **103** of the first basic flat-stick piece **100a**. The other end of first basic flat-stick piece **100a** is connected (also not visible in the figures) via the other circular through hole **103** to the cylindrical peg **212** of flat wheel piece **200c**. It should be appreciated that the motion of structure **600** is facilitated by the modularity of the construction toy system.

It should be appreciated that a variety of connectors may be used. Embodiments, however, are not limited to the disclosed set of game assembly pieces, and may encompass other shapes that fall within the spirit and scope of the principles of this disclosure. Each game assembly piece may be provided with a color and may be composed of any

12

suitable material that will fall within the spirit and scope of the principles of this disclosure.

The present invention being thus described in terms of several embodiments and examples, it will be appreciated that the same may be varied in many ways. Such variations are not to be regarded as a departure from the spirit and scope of the invention, and all such modifications as would be obvious to one skilled in the art are contemplated.

The invention claimed is:

1. A modular construction toy system, comprising:
a plurality of toy assembly pieces and a plurality of pivotal-rods, at least a first of said pivotal-rods comprises an elongated cylindrically shaped central member and an engaging rod-tip extended away from the elongated cylindrically shaped central member, the engaging rod-tip comprising a diameter smaller than a diameter of the elongated cylindrically shaped central member; and at least a second of said pivotal-rods comprise a matching receiving cavity at each end of said central member configured to receive the engaging rod-tip; and each of said toy assembly pieces comprises identical thickness and a circumferential edge, wherein a plurality of straight receiving grooves are formed, inwardly, at said circumferential edge, and wherein said identical thickness is configured to fittingly fill the gap formed by said straight receiving groove,
wherein a selected toy assembly piece of said plurality of toy assembly pieces is configured to interlock with another toy assembly piece via respectively selected straight receiving grooves of both selected toy assembly pieces;
wherein at least one of said plurality of toy assembly pieces is a flat-stick piece comprising modularly connectable toy assembly pieces having at least one pair of through holes formed inside each of said modularly connectable toy assembly pieces, a pair of elongated flat faces, an elongated body with two elongated parallel edges, a longitudinal axis, and rounded ends having a respective straight end-groove formed with said through hole, said flat-stick piece comprises one or more pegs formed therewith and protruding outwardly perpendicularly to one of the two faces of said flat-stick piece or outwardly perpendicularly away from one or more straight elongated parallel edges of said flat-stick piece, along said longitudinal axis,
wherein said pair of through holes formed inside each of said modularly connectable toy assembly pieces have a unified dimension,
wherein said at least one pair of through holes are spaced apart by either a same distance, or by that a distance multiplied by an integer, and wherein said same distance of said pair of through holes renders the construction toy system to be modular; and
wherein a selected engaging rod-tip is configured to either fittingly interlock with another pivotal-rod via a respectively selected receiving cavity, or with a selected toy assembly piece via a respectively selected fitted through hole formed in said selected toy assembly piece.
2. The modular construction toy system of claim 1, wherein said circumferential edge is a circular edge.
3. The modular construction toy system of claim 2, wherein at least one of said plurality of toy assembly pieces is a flat, ring-shaped piece.
4. The modular construction toy system of claim 2, wherein at least one of said plurality of toy assembly pieces is a flat, oval shaped piece.

13

5. The modular construction toy system of claim 1, wherein said flat-stick piece comprises the pair of elongated flat faces, and wherein each of said end-grooves ends with said end-through hole.

6. The modular construction toy system of claim 5, wherein said flat-stick piece further includes connecting pegs that are protruding perpendicularly away from said one or more straight elongated parallel edges of said flat-stick piece.

7. The modular construction toy system of claim 5, wherein at least one of said plurality of toy assembly pieces is a flat, right angle U-shaped piece.

8. The modular construction toy system of claim 5, wherein at least one of said plurality of toy assembly pieces is an upright, right angle U-shaped piece.

9. The modular construction toy system of claim 5, wherein at least one of said plurality of toy assembly pieces is a flat, L-shaped piece.

10. The modular construction toy system of claim 5, wherein at least one of said plurality of toy assembly pieces is a flat, traversed-Z-shaped piece.

11. The modular construction toy system of claim 5, wherein at least one of said plurality of toy assembly pieces is an upright, traversed-T-shaped piece.

12. The modular construction toy system of claim 5, wherein at least one of said plurality of toy assembly pieces is a flat, bow-shaped piece.

13. The modular construction toy system of claim 1, wherein one or more of said toy assembly pieces have at

14

least one enclosed through hole that is formed at a central location with respect to the lateral dimension of said toy assembly pieces, and

wherein a selected pivotal-rod of said pivotal-rods is also configured to interlock with a selected toy assembly piece by engaging a selected engaging rod-tip of said selected pivotal-rod with a selected enclosed through hole of said selected toy assembly piece.

14. The modular construction toy system of claim 1, wherein at least one of said toy assembly pieces has at least one connecting peg that is protruding from said at least one toy assembly piece, and

wherein said at least one connecting peg is configured to fittingly interlock with a selected through hole of another selected toy assembly piece.

15. The modular construction toy system of claim 14, wherein said connecting peg is configured to fittingly interlock with a selected pivotal-rod by engaging said connecting peg with said receiving cavity of said selected pivotal-rod.

16. The modular construction toy system of claim 1, wherein said plurality of toy assembly pieces are selected from a group of toy assembly pieces including a flat-stick piece, a connector-piece, a flat wheel piece, a flat U-shaped piece, a narrow upright U-shaped piece, a wide upright U-shaped piece, a flat L-shaped piece, a flat traversed-Z-shaped piece, an upright T-shaped piece, a flat bow-shaped piece, an upright bow-shaped piece, a flat ring-shaped piece, a flat oval-shaped piece, an upright ring-shaped piece and an upright oval-shaped piece.
